Primary Examiner — Rhea Shields(74) *Attorney, Agent, or Firm* — Chang & Hale LLP(57) **CLAIM**

The ornamental design for an instrument tower, as shown and described.

DESCRIPTION

FIG. 1 is a top, front, left perspective view of an instrument tower;

FIG. 2 is a front view thereof;

FIG. 3 is a rear view thereof;

FIG. 4 is a left-side elevation view thereof;

FIG. 5 is a right side elevation view thereof;

FIG. 6 is a top plan view thereof; and,

FIG. 7 is a bottom plan view thereof.

In the drawings, the broken lines are for the purpose of illustrating portions of the instrument tower that form no part of the claimed design.
